UNITED STATES PATENT OFFICE.

ARCHIBALD J. STEWART AND HARRY N. STEWART, OF LOS ANGELES, CALIFORNIA.

MITTEN.

1,216,877.

Specification of Letters Patent. Patented Feb. 20, 1917.

Application filed November 16, 1915. Serial No. 61,760.

To all whom it may concern:

Be it known that we, ARCHIBALD J. STEWART and HARRY N. STEWART, citizens of the United States, residing at Los Angeles, 5 in the county of Los Angeles and State of California, have invented new and useful Improvements in Mittens, of which the following is a specification.

This invention relates to a mitten.

10 It is the object of this invention to provide a mitten which is especially adapted for use in protecting the hands when handling heated articles and which is especially applicable for use by bakers in handling 15 baking pans, trays, and the like, and workmen in general in handling hot tools and implements.

Another object is to provide a mitten having heat insulating qualities, which is simple 20 in construction and so designed as to economize material and labor in its manufacture so that a substantial mitten of this type can be produced at small cost.

A further object is to provide a mitten 25 which is padded with a heat insulating or resisting material having a palm and thumb portion in which the adjacent faces of said portions are continuous and free from seams, thereby enabling the padding of the 30 mitten at the juncture of the thumb and palm portions and at the same time increasing the wearing quality of the mitten at this point.

Other objects will appear hereinafter.

35 The invention is illustrated in the accompanying drawings in which:

Figure 1 is a view in perspective showing the front of the mitten with portions broken away to illustrate the padded construction 40 thereof.

Fig. 2 is a perspective view of the rear portion of the mitten.

Fig. 3 is a detail section of the mitten as seen on the line 3—3 of Fig. 1 in the direction indicated by the arrows.

Fig. 4 is a detail in perspective of the thumb portion of the mitten showing how the material forming the palm portion of the mitten is continued to form the inner 50 face of the thumb of the mitten without a seam.

Fig. 5 is an enlarged detail section through the thumb of the mitten as seen on

the line 5—5 of Fig. 1 in the direction indicated by the arrows. 55

Fig. 6 is a view in elevation of the blank from which the palm and inner face of the thumb portion of the mitten is formed.

Fig. 7 is a view of the blank of the lining which is secured at its edges to the blank 60 shown in Fig. 6 with which it corresponds.

Fig. 8 is a view of the blank of insulating material such as sheet asbestos or the like which is interposed between the blanks shown in Figs. 6 and 7. 65

Fig. 9 is a view of the blank forming the back of the thumb portion.

Fig. 10 is a view of the blank forming the back portion of the mitten which receives the finger tips. 70

In carrying out the invention, a blank 11 is formed, shown in Fig. 6, of a suitable material preferably leather, which is fashioned from a substantially rectangular sheet of material, one end of which is scalloped 75 to form an arcuate edge 12 which is flanked at each end with arcuate edges 13 adapted to be folded rearwardly and to be secured to the edge 12 by stitching or the like, as shown in Fig. 2; the blank being designed 80 to be folded along fold lines indicated by the dotted lines *a* and *b* in Fig. 6. The material extending between the fold lines *a* and *b* constitutes the palm portion 14 of the mitten and the material extending between the fold lines *a* and *b* and the longitudinal edges *c* and *d* of the blank form the side portions 15 of the mitten, adapted to extend a short distance over the back of the 85 hand and wrist. The blank 11 is formed with a downwardly extending substantially parabolic-shaped or U-shaped cut 16 forming a correspondingly shaped flap 17 which constitutes the inner face of the thumb portion 18 of the mitten. 90

The U-shaped cut 16 is arranged adjacent one of the side flaps 15 and is enlarged at its terminals to form eyelets or perforations 16' by which a sufficient amount of the material is cut away at the base of the flap 17 to permit its being bent back toward the palm portion without buckling or drawing the flap and palm portion out of shape. 100

A blank 19 of suitable material, preferably leather, substantially corresponding in outline to the blank 11, is provided to form 105

a lining for the latter and is secured thereto at its marginal edges and along the edges of the cut 16 by suitable stitching. Interposed between the blanks 11 and 19 is a sheet 20 of asbestos or similar fire-proof material of a configuration substantially that shown in Fig. 8, being formed of a rectangular sheet and rounded at one end to correspond to the rounded end portion 12 of the blank 11 and cut away at one side to form a flap 21 which will extend between the flaps 17 of the blanks 11 and 19, as particularly shown in Fig. 5. In forming the thumb portion 18 of the mitten the flap 17 with its lining and padded flap 21 is turned upwardly, as shown in Fig. 1, and the open space bordered by the cut 16 in the blank 11 is filled by a blank 22 shown in Fig. 9, which is stitched to the marginal edge of the cut 16 and is extended upwardly along the back of the flap 17 of the lining blank 19, and stitched to the marginal edge of the flap, as particularly shown in Figs. 1 and 5, thus forming a member for the reception of the thumb. A blank 23, shown in Fig. 10, is stitched to the rounded end of the blank 11 and is attached at its edges to the side flaps 15, as particularly shown in Fig. 2, forming a covering for the finger tips.

As a means for fastening the mitten on the hand, it is provided with a pair of straps 24 which are stitched or otherwise secured to one of the side members 15 and passed through metallic loops 25 on the other flap 15. The outer ends of the straps 24 are fitted with socket members 26 of ordinary glove fasteners, which are adapted to receive the spring studs 27 of the fasteners, a pair of which are provided on each strap so that the straps may be adjusted.

By the foregoing described construction the mitten is formed with a palm portion which continues into the inner face of the thumb portion, as particularly shown in Fig. 4, without a seam joint, and the palm portion with its connecting wrist and thumb portions are padded with a heat resisting material which need not be stitched to the mitten because it is held in place by the flap portion 21 thereof extending within the thumb piece 18 and by the marginal edge of the cut-away portion of the blank 20 engaging the seam connecting the edge of the cut 16 of the blanks 11 and 19. The blank 22 forming the back of the thumb piece 18 is provided with perforations 28 which serve as vents for the thumb member.

While we have described the invention as applied to a mitten, it is manifest that a glove could be formed by dividing the palm portion of the blank into finger portions as is common in glove construction, and that other changes in construction may be resorted to as occasion requires without de-

parting from the spirit and scope of the invention as set forth in the appended claims.

What we claim is:

1. A mitten, comprising a palm portion, a flap struck from said palm portion adapted to form the inner face of a thumb receiving member, said palm portion formed with cut-away portions at the juncture of the edges of the flap, and a sheet of heat insulating material forming a backing for said palm portion and flap. 75

2. A mitten, comprising a palm portion, a flap struck from said palm portion adapted to form the inner face of a thumb receiving member, said palm portion formed with cut-away portions at the juncture of the edges of the flap, and a sheet of heat insulating material forming a backing for said palm portion and flap, and a blank affixed to the edges of the flap to form the back portion of 80 the thumb receiving member. 85

3. In a mitten, a substantially rectangular blank having a U-shaped cut terminating in perforations and forming a flap adapted to be folded on the face of the blank to form the inner wall of a thumb piece, a lining blank corresponding to the first named blank stitched to the latter at its edges, and a sheet of heat insulating material interposed between said blanks. 90

4. A mitten comprising a pair of corresponding blanks having U-shaped cuts terminating in perforations and forming flaps adjacent one edge of the blanks, said blanks stitched together on their edges and along the edges of the flaps, a sheet of heat insulating material interposed between said blanks and extending between the flap portions thereof, a blank stitched to the marginal edges of the cut in the aforesaid blanks and to the edges of the flap to form the back of a thumb receiving member, and means for fastening the blanks on the hand. 100

5. A mitten, comprising a pair of corresponding blanks having U-shaped cuts terminating in perforations and forming flaps, said blanks stitched together on their edges, a sheet of heat insulating material interposed between said blanks and extending between the flap portions thereof, a blank 110 stitched to the marginal edges of the cut in the aforesaid blanks and to the edges of the flap to form the back of a thumb receiving member, said first named blanks being folded along their longitudinal edges to form 115 side members, and fasteners connecting the adjacent edges of the folds for attaching the mitten to the hand. 120

6. In a mitten, a palm portion having a U-shaped cut adjacent one edge thereof terminating in cut-away portions forming a flap adapted to be turned toward the palm portion to form the inner face of a thumb receiving member, a heat resisting lining for said palm portion having a flap formed 125

thereon to conform to the thumb flap, an inner lining member corresponding in shape to the palm portion and secured thereto at its edges, having a flap stitched at its edges to the flap of the palm portion, and a blank stitched at its edges to the flaps extending over the opening formed by the U-shaped

cut, and stitched at its edge along the edge of the latter.

In testimony whereof we have signed our names to this specification.

ARCHIBALD J. STEWART.
HARRY N. STEWART.
